Specification for Design.

Patented May 5, 1914.

Application filed February 2, 1914. Serial No. 816,112. Term of patent 14 years.

To all whom it may concern:

Be it known that I, ALEXANDER L. WALTENSPERGER, a citizen of the United States, residing in Detroit, county of Wayne, State of Michigan, have invented a new, original, and ornamental Design for Closet-Seats, of which the following is the specification, reference being had to the accompanying drawing, forming part thereof.

Fig. 3 is a longitudinal sectional view on line 3—3 of Fig. 1 looking in the direction of the arrows.

I claim:

The ornamental design for a closet seat, as shown.

ALEXANDER L. WALTENSPERGER.
